UNITED STATES PATENT OFFICE.

CHARLES F. DITTMAR, OF MILWAUKEE, WISCONSIN.

CHILD'S CARRIAGE.

SPECIFICATION forming part of Letters Patent No. 645,251, dated March 13, 1900.

Application filed September 5, 1899. Serial No. 729,468. (No model.)

To all whom it may concern:

Be it known that I, CHARLES F. DITTMAR, a citizen of the United States, and a resident of Milwaukee, in the county of Milwaukee and State of Wisconsin, have invented certain new and useful Improvements in Children's Carriages; and I do hereby declare that the following is a full, clear, and exact description thereof.

10 My invention relates to vehicles for children; and it consists in certain peculiarities of construction and combination of parts, as will be fully set forth hereinafter and subsequently claimed.

15 In the drawings, Figure 1 is a vertical longitudinal sectional view, taken on the line 1 1 of Fig. 2, through the body of a child's carriage embodying my invention. Fig. 2 is a vertical transverse sectional view of the same, taken on the line 2 2 of Fig. 1.

Referring to the drawings, A represents the upper or seat part, and B the lower or foot part, of a child's carriage, said parts being of any ordinary and well-known construction.

25 C C represent parallel side rails which extend beneath the base D of the carriage and which project slightly in front of the rear wall of the lower part B thereof.

30 E E designate a pair of rack-bars or stepped supports secured so as to extend below the plane of the base D of the upper part of the carriage, and F represents the adjustable step or foot-rest, the latter being provided at its ends with transverse strips b b, the projecting rear ends of which are formed with oblique slots c therethrough for travel on the said rack-bars, the forward walls of said slots engaging with any desired steps d d of the rack-bars and the rear walls of said slots 35 forming stops against the rear edge of the

rack-bars, whereby the said step F is held by its own weight at any elevation to which it has been adjusted.

By means of my invention the step may be adjusted according to the length of the legs 45 of the occupant and the comfort of the latter thereby greatly enhanced and extra cushions or other like devices for this purpose dispensed with, and the required adjustment can be quickly and easily made without the 50 use of any tools or extraneous devices.

Having thus described my invention, what I claim as new, and desire to secure by Letters Patent, is—

1. In a child's carriage, the combination 55 with the body thereof, of a pair of inclined rack-bars or stepped supports, and an adjustable step or foot-rest provided with transverse strips formed with oblique-walled slots through their projecting rear ends for travel 60 upon said rack-bars and engagement with the steps thereof.

2. In a child's carriage, the combination 65 with the body thereof, of a pair of stationary inclined rack-bars, secured one at each side of said carriage-body, a step arranged transversely to said rack-bars; and a pair of strips secured, one at each end, to said step, and having rearwardly-projecting ends formed with oblique-walled slots therethrough for 70 adjustable engagement with said rack-bars.

In testimony that I claim the foregoing I have hereunto set my hand, at Milwaukee, in the county of Milwaukee and State of Wisconsin, in the presence of two witnesses.

CHARLES F. DITTMAR.
